UNITED STATES PATENT OFFICE.

EDWARD WAGNER, OF ST. LOUIS, MISSOURI, ASSIGNOR TO PAUL LEHMANN, OF ST. LOUIS, MISSOURI.

COMBINATION-LOCK FOR MOTOR-VEHICLES.

1,233,825.

Specification of Letters Patent. Patented July 17, 1917.

Application filed December 14, 1916. Serial No. 136,930.

To all whom it may concern:

Be it known that I, EDWARD WAGNER, a citizen of the United States, residing at the city of St. Louis, in the State of Missouri, have invented certain new and useful Improvements in Combination-Locks for Motor-Vehicles, of which the following is a specification.

The object of this invention is to prevent the stealing of motor vehicles, motor boats, aeroplanes, and the like, and for this purpose an imitation of the combination lock customarily found on safes, vaults, and the like is used in conjunction with means for shutting off the flow of gasoline or other motive fluid when it is desired to lock the machine and to open the same when the owner desires to proceed.

In the accompanying drawings forming part of this specification and in which like numbers of reference denote like parts wherever they occur,

Figure 1 is a side elevation showing the combination buttons on the instrument-board of a motor vehicle and one means for connecting the same with the gasoline control;

Fig. 2 is a detail of the said combination buttons;

Fig. 3 is a side elevation illustrating a different arrangement of combination buttons and their relation to the instrument-board of a motor vehicle and a different means of connecting the same to the gasoline control;

Fig. 4 is a horizontal sectional view through the lock valve device for controlling the gasoline flow;

Fig. 5 is a sectional view on the line 5—5 in Fig. 4;

Fig. 6 is a sectional view on the line 6—6 in Fig. 4;

Fig. 7 is a sectional view of an alternative form of device for controlling the flow of the gasoline;

Fig. 8 is a sectional view illustrating the principle of this invention applied to the control of electricity in an electrically-driven vehicle or boat;

Fig. 9 illustrates the true combination indicator;

Fig. 10 illustrates a superimposed arbitrary indicator;

Fig. 11 illustrates the plate bearing the arbitrary combination indicator in position 55 to cover the true combination indicator; and

Figs. 12, 13, and 14 illustrate another form of true and false combination indicators and means of covering the true or permanent indicator by the false or movable. 60

For convenience of description, this invention will be described as applied to a motor-driven vehicle in which a liquid fluid such, for instance, as gasoline (although other fluids may be used) is used for motive power, although it will be obvious that this invention will be equally serviceable in locking motor boats, aeroplanes, and the like and electrically-driven vehicles, boats, aeroplanes, etc. This invention will be 70 adaptable, also, for the same purpose if compressed gas be used as the motive fluid. If for any reason it is desired to lock a stationary engine from use, this invention can be applied thereto. 75

The gasoline line 1 leads from the gasoline source of supply to the carbureter 2, and is caused to pass through the box 3, in which are located two, three, or more cocks 4 pierced by the passage 5. When the cocks 80 4 are turned to the position shown in full lines in Fig. 4 (which corresponds to the position shown in Fig. 5, also), the gasoline line is open, so that the fluid will flow to the carbureter; but when the cocks 4 are 85 turned off that position, the gasoline line is closed, as indicated, for instance, by the position of the passages 5 shown in dotted lines in Fig. 4. The box 3 is interposed in the said gasoline line by the screw-threaded ends of the pipe being screwed into the screw-threaded sockets 6 in the wall of the box 3. The diameter of the passages 5 is the same as the internal diameter of the gasoline pipe line, and as this diameter is 90 not very great, a slight movement of one of the cocks 4 will cause non-registration of the passage 5 contained therein with the rest of the gasoline pipe line. The principle of the device illustrated in Fig. 7 100 is the same as what has hereinabove been described, the only difference being that registration or non-registration of the passages 5 either with each other or with the outside parts of the pipe line is caused by the serpentine arrangement of the passages 5 and 105

non-registration thereof when the said serpentine arrangement is disturbed by rotation of the cocks 4.

In Fig. 8, blocks 7 of any shape of insulating material are substituted for the cocks 4 shown in the other figures, and are located in the line of electric flow between the cables 8 and 9, the ends of which are socketed in the said box 3. When open for 10 the flow of the electric fluid, the ends of the different parts of the conductor 10 register in alignment and allow the electric flow; but a turn of one or more of the insulation blocks 7 from the position shown in Fig. 15 8 will break the conductor and interrupt the flow of the electric current.

A plate 11 sweated or soldered on the bottom of box 3 prevents ready and quick tampering with the nuts 12, which is enough in 20 most cases to prevent theft of the vehicle protected by this device, inasmuch as the time for getting the engine started and making off with the vehicle is not long enough for dismemberment of the gasoline control 25 device and study of the location of its passageways 5 or conductors 10.

If the box 3 and its contained parts are located immediately underneath the driver's hand, the stems 13 may be lengthened so as 30 to enable a direct vertical connection from the combination buttons 14 to the cocks 4 or insulator blocks 7. It is, however, more or less customary in motor vehicle construction to place such devices as the combination buttons 14 upon the instrument-board 15, and for that reason there are illustrated in Figs. 1 and 3 means for rotating from the combination buttons 14 on the instrument-board 15 the stems 13 and thereby the cocks 4 and 35 insulator blocks 7. In Fig. 1, three shafts 16 are connected by universal joints 17 to the three pitmen 18, which in turn are connected by the universal joints 19 to the stems 13. Rotation of the buttons 14 causes 40 rotation of the cocks 4 by means of the said intermediate devices.

In Fig. 3 is illustrated a different arrangement of combination buttons 14, the outer one of which rotates the hollow shaft 20, 50 the intermediate one of which rotates the hollow shaft 21 contained within the said shaft 20, and the inner one of which rotates shaft 22 contained within shaft 21. The order of attachment of the said buttons to 55 the said shafts is, of course, immaterial, and may be reversed or varied. Pinions 23 are operated by the said shafts 20, 21, and 22 and engage gears 24, and by said means rotate shafts 25, which are extensions of stems 60 13. Thereby cocks 4 or insulation blocks 7 may be rotated.

By setting the combination buttons 14 at an oblique angle to the instrument-board, 65 shafts may be run direct to box 3, the angle of which would in that event also be

changed, and there would be a direct-acting straight shaft from the said buttons to the cocks 4 or blocks 7.

While the drawings illustrate some parts as vertical and others as horizontal, it is 70 to be understood that re-arrangement of the parts in these respects and with respect to the various angles at which they may be placed and their relative location with regard to each other can be greatly varied. 75

The combination may be changed in case of need, as, for instance, in the case of change of employees. In the device illustrated in Fig. 3, this will be accomplished by removing one or more of the pinions 23 80 from the shaft or shafts bearing the same, and then turning the said shaft or shafts any desired distance, so as to change the relation of the parts on the buttons 14. In the device illustrated in Figs. 9, 10, and 11, 85 the plate 26 bears one set of combination numbers that are visible, and the said plate is countersunk in the button 14 and covers a set of fixed combination numbers (see Fig. 9) that are marked within the said 90 countersink, but which are normally covered over by the said plate 26. The set of combination numbers on plate 26 do not register with the same numbers in the set of combination numbers marked within the 95 said countersink. A person familiar with using the lock with the combination that could be operated by the set of numbers appearing on plate 26 would be at a loss to know how to operate the same if by loosening the screw 27 and turning the plate 26 a new relation had been established between the true and the inner combinations.

Figs. 12, 13, and 14 illustrate a different mode of attaching plate 26 to button 14, the 105 same being here done by forcing flanged ring 28 upon button 14 so as to hold plate 26 in place.

It will be understood that the relation of the passageways 5 or conductors 10 is fixed and 110 can be discovered by dismantling the line of fluid flow, removing box 3, opening the same, and removing nuts 12 and parts 4 or 7, and thereupon studying the relation of the connecting parts for fluid flow; but 115 this is in general unpractical, because the limit of time within which the person who unwarrantedly desires to set the motor in operation has to work is as a rule too short to permit prolonged tampering with the 120 lock or other manipulation of the motor.

While the drawings illustrate and the description has referred to a plurality of combination buttons 14, it will be understood that the combination worked by only one 125 button or similar device will to a certain extent serve the purpose of this invention. It, however, becomes more difficult to work the combination and more difficult to defeat the purpose of this invention where two 130

buttons and corresponding parts are used. When the combination is further complicated by the use of three sets of parts, as illustrated in the drawings, the difficulty 5 has been increased in geometrical progression and to a point where it is practically impossible within the time limit that needs to be considered to defeat the purpose of this invention.

10 It will be noted that in the drawings the passages 5 are off center (see Figs. 4 and 6), as thereby a more complicated combination is produced, the same never registering for a through passage from end to end of 15 box 3 except when the combination has been exactly set. This is the location, also, of conductors 10. If the same were through the center of the parts 4 or 7, the connection would be established twice in each rotation 20 of a part 4 or 7; but set off center, as shown in the drawings, the passages 5 or conductors 10 will not register with each other except when once in the rotation of each 25 part 4 or 7 and when the next adjoining part 4 once in its rotation has been brought to the proper alignment. On account of the nature of the passages 5 shown in Fig. 7, registration and communication there-through will be effected only once in the rotation of the parts 4 and only when they 30 have all been properly rotated in accordance with the combination so as to produce registration and communication.

Having thus described this invention, I 35 hereby reserve the benefit of all changes in form, arrangement, order, or use of parts, as it is evident that many minor changes may be made therein without departing from the spirit of this invention.

40 I claim:

1. A motor lock comprising rotatable means for interrupting the flow of the motive fluid at spaced points, independently operable means for operating the same, a 45 button on each operating means having combination numbers thereon, and an adjustably-mounted plate on each button arranged to conceal the combination numbers on the latter and provided with combination numbers 50 adapted to be positioned to be out of registry with the numbers of the button whereby the position of each button may apparently be changed by adjusting the superposed plate without, in fact, altering the position of said button.

55 2. An operating element comprising a portion having permanent characters thereon indicative of a fixed combination and a

settable member secured thereto in position to conceal said characters, said settable member having characters thereon indicative of a combination.

60 3. An operating element comprising a stem and a head fixed thereto; said head having permanent characters thereon indicative of a fixed combination, and an adjustable plate rotatively mounted with respect to said head and carrying characters indicative of a changeable combination.

65 4. A device of the character described comprising a valve casing, a plurality of side by side valve plugs rotatively mounted therein, and a straight passage formed complementally through the casing and plugs and lying to one side of the centers of said 70 plugs so that while a straight and unbroken passage is provided those portions of the passage in the several plugs will register with the remainder thereof once only in a revolution of said plugs and an actuating 75 means for each of the valve plugs having means for indicating the positions of the plugs.

80 5. A device of the character described comprising a valve casing and a plurality of side by side valve plugs mounted to turn 85 therein, said casing and plugs having a passage formed complementally therethrough, those portions of the passage formed in the several plugs extending in a straight line 90 through the plugs and those portions of the passages formed in the casing being so located that the passages in the plugs register therewith once only in a revolution and an actuating means for each of the valve plugs 95 having means for indicating the positions of the plugs.

6. A device of the character described comprising a valve casing and a plurality of side by side valve plugs mounted to turn 100 therein, said casing and plugs having a passage formed complementally therethrough, those portions of the passage formed in the several plugs extending in a straight line 105 off center through the plugs and those portions of the passage formed in the casing being disposed in such position that the passages in the several plugs register with the passages in the casing once only during a revolution of the said plugs and an actuating 110 means for each of the valve plugs having means for indicating the positions of the plugs.

In testimony whereof I hereunto affix my signature.

EDWARD WAGNER.
